US0D1063119S

(12) **United States Design Patent** (10) **Patent No.:** **US D1,063,119 S**
(45) **Date of Patent:** **** Feb. 18, 2025**

(54) **JOINT FORMER**

(71) Applicant: **Illinois Tool Works Inc.**, Glenview, IL (US)

(72) Inventor: **Darrell A. Wiatrowski**, Libertyville, IL (US)

(73) Assignee: **Illinois Tool Works Inc.**, Glenview, IL (US)

(**) Term: **15 Years**

(21) Appl. No.: **29/855,296**

(22) Filed: **Sep. 30, 2022**

(51) LOC (15) Cl. **25-99**

(52) U.S. Cl.

USPC **D8/354; D25/199**

(58) **Field of Classification Search**

USPC D25/121, 199, 128, 123, 159; D8/16, D8/354, 349, 135, 380, 382, 366, 394, D8/383, 384, 385

CPC .. E01C 11/106; E01C 2201/16; E01C 11/126; E04B 1/6807; E04B 1/6804

(57) **CLAIM**

The ornamental design for a joint former as shown and described.

DESCRIPTION

FIG. 1 is a top perspective view of a joint former of one embodiment of my new design.

FIG. 2 is a bottom perspective view of the joint former of FIG. 1.

FIG. 3 is a right side view of the joint former of FIG. 1.

FIG. 4 is a left side view of the joint former of FIG. 1.

FIG. 5 is top view of the joint former of FIG. 1.

FIG. 6 is bottom view of the joint former of FIG. 1.

FIG. 7 is a front view of the joint former of FIG. 1.

FIG. 8 is a rear view of the joint former of FIG. 1.

FIG. 9 is a top perspective view of a joint former of another embodiment of my new design.

FIG. 10 is a bottom perspective view of the joint former of FIG. 9.

FIG. 11 is a right side view of the joint former of FIG. 9.

FIG. 12 is a left side view of the joint former of FIG. 9.

FIG. 13 is top view of the joint former of FIG. 9.

FIG. 14 is bottom view of the joint former of FIG. 9.

FIG. 15 is a front view of the joint former of FIG. 9; and, FIG. 16 is a rear view of the joint former of FIG. 9.
